(57) **CLAIM**

The ornamental design for a mirror, as shown and described.

DESCRIPTION

FIG. 1 is a front elevational view of a mirror according to an embodiment of the invention.

FIG. 2 is a top plan view thereof; and,

FIG. 3 is a left side elevational view, the right side elevational view being a mirror image thereof.

The bottom and rear elevational views thereof being plain and unornamented.
